UNITED STATES PATENT OFFICE.

JEHANGIR MANECKJI COOPER, OF BOMBAY, INDIA.

PRINTING PROCESS AND APPARATUS THEREFOR.

Application filed October 25, 1923, Serial No. 670,632, and in Great Britain October 28, 1922.

This invention relates to the printing of designs or patterns on paper, cloth, or other material.

In Letters Patent of the United States, No. 5 1,359,034, granted to me on November 6, 1920, I have described a process of printing in which the material is printed at the point of contact with a metal ink-carrying cylinder or roller with a plain surface over which 10 the ink is evenly distributed, the pattern being in relief on the surface of another roller pressing against the reverse side of the material.

The present invention comprises a printing process in which the design or pattern is first formed in a film of ink or colour on a plain, smooth, hard surfaced roller covered all over with a thin film of ink or colour, and then transferred from this plain surface 20 to the material to be printed by passing this material under suitable pressure between this plain surface and another plain roller preferably with a smooth, resilient surface.

The invention will be fully described with 25 reference to the accompanying drawings.

Fig. 1. Sectional elevation of machine more adapted for printing according to the invention with water colours or dyes.

Fig. 2. Diagrammatic section showing machine more adapted for printing with oil colours.

Fig. 3. Sectional elevation similar to Fig. 1 illustrating the use of an air brush for applying an additional colour.

The apparatus adapted to operate the process is constructed with a hard metal cylinder or roller A with a plain, smooth, hard surface, over which a film of colour or ink is evenly distributed by suitable means. A 35 second cylinder or roller B, preferably of resilient material such as rubber or composition with a plain, smooth, resilient surface rotates with the cylinder or roller A and is pressed against it by a lever C and weight 40 W or by a screw, eccentric, spring, or other means.

The ink or colour is distributed evenly in a film of even thickness over the surface of the cylinder or roller A by any known means, 50 such as by a number of inking rollers d d^1 from an ink container D (Fig. 2), or by a roller D^1 pressed against the cylinder A (Fig. 1), as described and claimed in my application filed Oct. 26, 1923, Serial No. 55 670,831. According to this latter method of applying the film of colour a body of col-

ouring liquid D^2 is supported between the coacting revolving rollers A and D^1 , roller A being a printing roller, and roller D^1 serving to squeeze a portion of the colouring 60 liquid D^2 into a thin film which is carried along on the surface of the printing roller A.

The design or pattern to be printed on the material E is formed or traced in the film of ink on the surface of the hard cylinder or roller A by any known means, such as by dabbing something against the ink, or by holding a comb or brush against it, or by a roller F with a pattern which will lift or absorb or remove part of the ink, or by a 70 revolving brush or reciprocating comb applied mechanically or by hand. The pattern roller F may be an engraved roller of gelatine, rubber, wood, or even metal, or it may be a plain roller covered with lace or the 75 like, or with an absorbent material. With a pattern roller such as F a wiper roller f may be applied to remove colour that may accumulate thereon.

To produce a multi-colour effect, one or 80 more air brushes may be set to spray any desired colour or colours onto the even or uniform film previously applied to the surface of roller A, as above described. Such an arrangement is illustrated in Fig. 3 wherein an 85 air brush H is provided for applying additional colour in the form of a spray H^1 onto the uniform film of colour previously applied to the surface of roller A from the pool of colouring liquid D^2 . It will be understood 90 that the air brush H may be manipulated by the hand of the operator, or motion may be otherwise imparted thereto, for the purpose of applying the spray in such a way as to form a desired pattern, such, for example, 95 as a mottled effect.

In certain cases the preliminary uniform film of colour on the roller A may be entirely dispensed with, and, instead, one or more air brushes may be arranged to spray 100 the colour on roller A, thus obtaining certain types of effect which may be transferred onto the printing material in the manner described above. In place of spraying, dabbing also may be resorted to to give 105 mottled or marble effects.

The process of this invention is also carried out by printing the negative or reverse pattern from the ink carrying cylinder a described in my patent above referred to.

As previously mentioned the design or pattern of ink or colour which has been

formed on the surface of the roller A in any of the various ways just described is transferred to the material to be printed by passing this material between the surface of roller A holding the design and another plain surfaced roller. The roller A in both Figs. 1 and 2, as has been seen, revolves in the counter clock-wise direction, and the surface of this roller after leaving roller F 10 contains in ink or colour the design or pattern to be printed. The rotation of roller A brings this portion of its surface continuously into contact with the web E of material to be printed as it is fed by the rollers A and B. The roller B which preferably has a resilient surface presses the material to be printed against the roller A and causes the pattern or design to be printed on the side of the web which contacts with roller 20 A by the transference of the ink or colour which has been arranged on the surface of this roller in the form of the design.

The roller A continuing its counter clock-wise revolution carries the surface thereof which has operated upon the web E past the scraping devices G where any excess colour, remaining after the printing operation, is removed. Ink or colour which is removed by the scraping device G is collected in vessels 30 g. The surface of roller A after it has passed the scraping device is left clean ready for another application of the film of ink or colour.

What I claim as new and desire to secure by Letters Patent of the United States is:—

1. The process of printing designs or the like upon paper, cloth, or other material, which comprises, maintaining a body of colouring liquid at a fixed point in contact 40 with the surface of a revolving printing roller, allowing a thin film of said liquid to be carried along with the roller, modifying said film to form a desired design to be printed, and transferring the modified film 45 to the material to be printed.

2. The process of printing designs or the like upon paper, cloth or other material, which comprises, supporting a body of coloring liquid at a fixed point upon the surface of a revolving printing roller, allowing a thin film of said liquid to be carried along with the roller, modifying said film to form a desired design to be printed, and transferring the modified film to the material to be printed.

3. The process of printing designs or the like upon paper, cloth or other material, which comprises, supporting a body of coloring liquid between a pair of coacting revolving rollers one of which is a printing roller, allowing a portion of said liquid to be squeezed into a thin film by the coaction of said rollers onto the surface of the printing roller and carried along with said

roller, modifying said film to form a desired 65 design to be printed, and transferring the modified film to the material to be printed.

4. The process of printing designs or the like upon paper, cloth, or other material which comprises, applying a uniform film of 70 colouring liquid to a printing roller having a smooth, hard surface, adding to the said film colouring liquid to produce a design, and passing the material to be printed between said printing roller and a pressure 75 roller.

5. The process of printing designs or the like upon paper, cloth, or other material, which comprises, maintaining a body of colouring liquid at a fixed point in contact 80 with the surface of a revolving printing roller, allowing a thin film of said liquid to be carried along with the roller, applying additional colouring liquid to said film to form the desired design, and passing the 85 material to be printed between said printing roller having colouring liquid thus applied thereto and a pressure roller.

6. The process of printing designs or the like upon paper, cloth, or other material, 90 which comprises, maintaining a body of colouring liquid at a fixed point in contact with the surface of a revolving printing roller, allowing a thin film of said liquid to be carried along with the roller, spraying 95 additional colouring liquid onto said film to form the desired design, and passing the material to be printed between the printing roller having the colouring liquid thus applied thereto and a pressure roller.

7. The process of printing designs or the like upon paper, cloth, or other material which comprises, applying a film of colour to a smooth, hard, printing surface, spraying additional colour onto said film to produce a desired design, and passing the material to be printed between said printing roller having colour thus applied thereto and a pressure roller.

8. An apparatus for printing designs or the like upon paper, cloth, or other material comprising, a printing roller having a smooth, hard surface, a roller coacting therewith for maintaining a pool of color in continuous contact with the printing roller and for squeezing a portion of said color between said rollers into a film of substantially uniform thickness on the surface of the printing roller, means for modifying said film for producing designs on the said printing roller, a pressure roller cooperating with said printing roller, and having a smooth, resilient surface, and means for feeding the material to be printed between said printing and pressure rollers.

In testimony whereof I affix my signature.

JEHANGIR MANECKJI COOPER.
